United States Patent Office

Des. 233,179
Patented Oct. 8, 1974

233,179

PROJECTOR CARRYING CASE

James H. Sias, Rochester, N.Y., assignor to Eastman
Kodak Company, Rochester, N.Y.

Filed Feb. 7, 1972, Ser. No. 224,391

Term of patent 14 years

Int. Cl. D3—99

U.S. Cl. D87—5 E

FIG. 1

FIG. 2

FIG. 3

FIG. 4

FIG. 1 is a top perspective view of a projector carrying case showing my new design;

FIG. 2 is a bottom perspective view thereof showing the side and end not seen in FIG. 1;

FIG. 3 is an end elevational view thereof; and

FIG. 4 is a side elevational view thereof.

I claim:

The ornamental design for a projector carrying case, as shown.
